UNITED STATES PATENT OFFICE

THOMAS L. LOWE, OF DEVON, CONNECTICUT, ASSIGNOR TO THE LOWE MACHINERY COMPANY, OF BRIDGEPORT, CONNECTICUT, A CORPORATION OF CONNECTICUT

APPARATUS FOR LAUNDERING

Application filed September 17, 1926. Serial No. 136,110.

This invention relates to a method and apparatus for laundering by which the washing of the several classes of goods such as whites, lights and darks are maintained entirely separate and by which correct reassembly of the goods of the several classes in each wash is facilitated. The apparatus may be used both as a washing and drying machine of large capacity fitted to meet all the requirements of commercial uses.

While detached from the washing machine, thus adapting the clothes to be quickly distributed and deposited therein and removed therefrom. I also provide means whereby these several containers each including a series of compartments for the wash may be placed in one end of the washing machine and removed from the opposite end. This handling or loading and unloading operation is best done simultaneously, by shoving out a

The invention has been designed not only with a view of washing large quantities of work per hour or day, but is particularly suited to save labor in handling the work. With these and other objects in view the invention resides and consists in the construction and novel combination and arrangements after the washing and drying operation. With this saving in mind it is possible, by the use of my machine, after the bundles of customers' clothes have been weighed, to separately classify and distribute each bundle in three separate compartments, where they remain throughout the washing and drying process. After these operations are completed, the several series of compartments are brought forward in their proper order so that the same relative three compartments may be opened and the three kinds of clothes therein belonging to the one customer presented for removal, thereby preventing the clothes of one customer becoming mixed with those of another.

An object of the invention is to provide a washing machine which may be quickly loaded and unloaded and thus kept in actual operation, the bigger part of a day, and in a way to avoid the great loss of time now experienced in opening up and loading the more popular types of wash wheels now employed.

With this object in view I have devised a means and method whereby all the assorting of the lights, darks and colored clothes of a bundle as they come into a laundry may be distributed into the several compartments

Fig. 1 shows a plan view of what I term a

three unit washing and drying machine constructed in accordance with the invention;

Fig. 2 shows a sectional elevation of one of the washers embodied in the layout shown in

Fig. 1;

Fig. 3 shows an enlarged detail cross sectional view taken on line 3—3 of Fig. 2;

Fig. 4 shows a similar enlarged detail cross sectional view through the axial portion of

the machine and taken through line 4—4 of Fig. 2;

Fig. 5 is an end view of the washer as seen from the left of Fig. 2;

Fig. 6 shows a cross section through the

washing machine, taken on line 6—6 of Fig. 2;

Fig. 7 is a side elevation, partly broken away, of the wash wheel shown in Figs. 2 and 6 and with the clothes receptacles removed;

Fig. 8 is an enlarged plan view of part of an end portion of one of the several perforated receptacles for receiving and carrying the clothes, while being tumbled and washed by the wheel, shown in Figs. 2, 6 and 7;

Fig. 9 is an end view of the receptacle shown in Fig. 8;

Fig. 10 shows a sectional side elevation of a portable and rotatable rack for carrying the several receptacles for containing and transporting the articles to be washed;

Fig. 11 is an end view of portable rack shown in Fig. 10;

Fig. 12 is a diagrammatical view of three of the rotatable racks each containing four clothes receptacles as shown in Figs. 8 and 9, and arranged in relative locations for the purpose of receiving the several different classes of articles, of a given customer's bundle, to be washed; and

Fig. 13 shows a modification in the form of a single receptacle or pocket for receiving articles to be washed and adapted for use in my washing machine.

I have deemed it advisable in illustrating the present invention to represent a three unit type of washing and drying equipment since I believe it to be the most practical and commercial form of installation, especially for large laundries, smaller laundries could perhaps use a two or even a one unit type of machine more economically.

The three unit type of machine layout, shown in Fig. 1, includes several associated portable racks for carrying the receptacles in which the articles to be washed are assorted, transported to and from the washing machine, and later distributed. The individual units of the washing machine as well as the portable racks are designed to hold four of these receptacles each arranged in spaced relation to the axis of the machine, and each receptacle includes a series of compartments in which different washes or different articles of the same wash are placed. These racks, see Fig. 1, serve as a convenient means for not only receiving and transporting the receptacles with articles to be washed, but also as a required means for the positioning of the receptacles in alignment with the ends of the washing machines preparatory to placing the receptacles in said machine for the purpose of washing the articles carried therein. These racks further serve to receive the receptacles after the cloths have been washed and dried and for the transporting and positioning of the receptacles to a location for the distribution of the clothing. These receptacles, of which but four are shown, in

the drawings, are each formed of perforated metal so that the water may flow through them freely, and are divided into a series of compartments generally triangular or sector shaped in cross section, preferably six in number, and each compartment is provided with a door through which the clothes can be put into and removed from the compartments.

In view of the similarity of the construction of the several washing units I will use similar reference characters upon each to indicate similar parts in describing in detail the several units, and follow this with a description of the common drive means the water supply and other cooperative features as are shown in the illustration of the multiple unit layout, as contained in the drawings.

Referring in detail to the characters of reference marked upon the drawings 12—12 represent end frame members which are substantially alike in construction and preferably formed of metal. These end members are provided with feet and together with an intermediate member 14 are seated upon the floor and serve to support and form a part of a large elongated cylindrical reservoir 13 which is preferably formed of sheet metal. This obviously forms the housing in which the wash wheel, carrying the removable containers, before referred to, are rotatably mounted. A suitable number of water outlet or drain pipes 15 are connected to the bottom of the reservoir while suitable vents 16 are located in the top. The water, chemicals and other ingredients may be supplied to these washers through the main and branch pipes 17 and 18 shown in Fig. 1.

The wash wheels of the several units are rotated by power furnished from a motor 19 which drives the shaft 20, carrying suitable worms 21 connected with and driving gears 22 upon the shaft 23 of each of the individual units. These shafts are supported in suitable brackets 24 and carry upon their outer ends relatively small gears 25 that mesh with and drive the larger gears 26 mounted upon the rotatable hollow shaft 27 of the wash wheel, as will later be more fully explained.

The end frame members 12—12 of the reservoir 13 are provided with extended and thickened aligned bearing portions 28 in which the before mentioned hollow shaft 27 is secured. The said shaft extends out beyond these bearing portions 28 for the attachment of the before mentioned gear 26 whereby the said hollow shaft and its wash wheel is rotated for the purpose of washing the clothing. To the ends of the said hollow shaft 27 is secured a suitable clutch member 29 for the connection thereto of a similar clutch member 30 of the portable racks.

The wash wheel contained within the reservoir is made up of three somewhat similar

spider-like members 130, 31 and 32, one of which is positioned at opposite ends of the wheel and the third rotated centrally. These spiders each include a hub portion 33 that is secured to the before mentioned shaft 27 in any suitable manner and having radially disposed spoke-like portions 34 preferably four in number, as shown in the drawings, which serve to support longitudinal guide members 35 and 36 between which the receptacles, for holding the clothes to be washed, are positioned as will later again be referred to. While these spiders and the wheel as a whole, of which they form a part, 10 can be constructed to form different numbers of pockets for the receptacles 37, yet I have preferably shown a construction with four pockets to accommodate four of these receptacles, which means that each of the spiders 15 includes four spokes and that the triangular or sector shaped spaces or pockets therebetween form openings in and through which the receptacles are placed. These pockets and the receptacles placed therein, are positioned in spaced relation to the center or 20 axis of the wash wheel so that the receptacles containing the clothes to be washed are revolved around said axis and are in no way in alignment with the axis proper. The cylindrical body of the reservoir in which the 25 wash wheel proper operates is closed except for the required pipe connections and thus has no doors in its cylindrical face whatever for the reception or removal of the clothes 30 to be washed. After the clothes to be washed are placed in the receptacles, said receptacles together with the clothes, are positioned in the washing machine by being inserted through an opening 38 in one end which is 35 normally closed by a door 39 mounted for vertical operation in guides 40 in one of the end frame members 12. There are two of these doors, one at each end of the machine, and in practice both are opened at once to 40 allow of the simultaneous introduction and removal of receptacles. These doors are normally closed by gravity and opened through the manual operation of a handle 41 and lever 42. The doors through which these 45 receptacles are inserted and removed are positioned in the upper end portions of the machine and above the level of the wash liquor and are designed to align with one of the pockets of the wash wheel when the latter is stationary and positioned to receive 50 said receptacles. As they do not extend below the level of the water they need not fit strictly water tight.

Channel iron strips 35 and 36 are preferably secured to the opposite side portions of the spokes or arms 34 to engage and guide the side portion of the receptacles, while the angle iron 36 attached to the opposite sides of the outer end portions of the spokes serves 55 for the engagement and guidance of the outer

parallel, longitudinal edge portion of the receptacles so as to retain them in their relative position during the operation of the wash wheel and also during the insertion and removal of the said receptacles.

In order to insure a free movement of the receptacles 37 into and out of the wash wheel I provide one or more series of rollers 43 upon which these receptacles are moved, said rollers being preferably mounted in one or more lengths of relatively small channel irons 44. The ends of these channel irons are loosely positioned in notches 45 in the hub of the spider so that the said channel irons with their series of rolls are free to move radially with respect to the axis of the wash wheel and in a way to engage and support the receptacles.

These channel irons and rollers 43 together with other mechanism, which I will next describe, also serve to lock the receptacles in position by forcing them out so that their parallel longitudinal edges will firmly grip the flanges of the angle irons 36 carried by the arms of the spiders. Referring now more particularly to Figs. 2 and 4 it will be seen that within the perforated hollow shaft 27 I provide a longitudinal rod 46 that is positioned centrally in alignment with the axis of the wash wheel and is mounted to rotate in suitable bearings 47 carried within the hollow shaft, said rod being threaded in part as at 48 to engage one of said bearings so that when a wrench or handle is applied to the outer headed end 49 of the said rod and is turned thereby, the said rod will be given a longitudinal movement throughout the length of the said hollow shaft around which the perforated receptacles are positioned. Upon this rotatable and longitudinally movable rod 46, I provide a suitable number of conical wedges 50 which are carried with the said rod in both its rotary and longitudinal movements. A series of radially disposed pins 51 are mounted in the hollow shaft around these conical wedges and against which they normally engage. I have shown four such pins in engagement with the wedges and one of each of this series of pins is in yieldable engagement with the channel strips 44 carrying rolls 43 to support the receptacles heretofore mentioned. Inasmuch as there are several of these wedges and associated pin connections located at suitable distances apart, the channel irons are properly supported throughout their length.

A spiral spring 52 is mounted on the said pin 51 intermediate of a shoulder 53 thereof and the underside of the channel iron 44 in a manner to normally hold the said channel iron and its rolls in a radially extended position so as to properly engage and support the inner longitudinal surface of the receptacles, as before noted.

The wash wheel, before referred to, is

mounted upon and rotates with the perforated hollow shaft 27 and, as before stated, includes hub members 33 that are directly secured to the said shaft and from which radiate spoke members 34, as heretofore described, and in addition I provide for each of said members a ring 54 secured to and surrounding the end portions of the spokes 34, said ring being so formed and applied as to form an annular band that conforms to the outer peripheral faces of the receptacles so that the same may be slid in under the band when being placed into or removed from the wash wheel. The receptacles 37, as preferably constructed are of a generally elongated tubular design, made of perforated sheet metal and of substantially triangular or sector shaped in cross section, to better fit into the quarter section pockets of the wash wheel. As shown these receptacles are each divided into a series of six compartments 55, each compartment being provided with a door 56 adapted to be closed during the washing operation and opened when the receptacles have been transferred to the portable racks 57 and positioned for unloading.

In Fig. 13 I have shown a modification of this feature of the invention in the illustration of a single compartment receptacle 58 adapted to be used with other similar receptacles in series and loaded into the pockets of the wash wheel, one against the other, from one end of the machine in the same manner that the larger receptacles are introduced, it being obviously apparent that these individual or smaller receptacles would be of a proportionate length to permit a desired number to be positioned in a single pocket. The machine as described is not only adapted for washing clothes when placed in the several compartments of the receptacles carried by the wash wheel but is also adapted to dry the same after being washed.

For the purpose of the washing operation, the machine would be filled with clothes as before described, and the reservoir filled with water through the pipe connections 17 and 18, before mentioned, to about the level of the shaft 46 whereupon the wheel is rotated backward and forward, the water then changed and the operation repeated, and finally when the washing operation is finished the water is drained out through the bottom pipe 15. Steam is then introduced through the pipe 59 and annular port 60 of the hub 28, through perforations 61 of the hollow shaft, and finally out through other perforations 62 of the same shaft so that said steam may be introduced centrally throughout the length of the washer in a manner to permeate the wet clothes and extract the water therefrom.

Referring now more particularly to Figs. 1, 10, 11 and 12 wherein I have illustrated the portable racks 57 for handling the receptacles, it will be seen that this rack is both

portable and rotary, that is, the rack proper comprises a rotatable member and which in turn is mounted upon a portable frame or truck which allows the rack in which the receptacles are mounted to be conveniently moved from one place to another. The truck includes a platform 63 which is mounted upon wheels 64 for carrying supports 65 in which the central alined bearings 66 are formed to receive a longitudinal shaft 67. Upon the ends of this shaft are secured clutch members 68 for connection to the before mentioned clutch member 29 of the wash wheel shaft 27, so that the pockets of the rack may be maintained in alinement with those of the wash wheel. This is of particular importance when the rack is but partially loaded with receptacles as otherwise it might be difficult, due to the lack of rotative balance of the rack frame when but partly loaded, to maintain the desired pocket therein in position opposite to the door opening in the reservoir to discharge into or receive a receptacle from the wash wheel. The rotatable rack is mounted upon this shaft 67 and between the before mentioned end supports 65 and is secured to rotate with the shaft. This rack is in part constructed somewhat after the style of the wash wheel in that it includes a plurality of spiders 69 comprising hub portion 70 mounted upon and secured to the before mentioned shaft 67, and radially disposed arms 71.

The arms of the several spiders are in alinement, one with the other, and connected by longitudinal guide strips 72 and angle iron 73 between and against which the receptacles are adapted to be placed and secured. The receptacles are placed in these racks by being shoved in from the end in substantially the same position and manner that they are placed in the wash wheels and are arranged in annular spaced relation to each other and likewise in spaced relation to the axis of the rotary member of the rack in which they are mounted.

A simple form of spring catch 74 may be attached to the outer face of the arms of the end spiders in a way to engage the face of the end of the receptacles to hold them against any slight tendency toward longitudinal displacement that might occur. A series of rollers 75 carried in brackets 76 secured to the central shaft 67 serve to support and facilitate the introduction and removal of the receptacles when slid into and removed from the racks. Each of these brackets is provided with a series of arms and rollers and the arms and rollers of the series of brackets are in alinement with each other so that one roll of each bracket will engage and support the inner face of a receptacle. These racks can be loaded with wash and unloaded to the best advantage when arranged in the formation shown in Fig. 12, in which case the

operator or distributor of the wash, stands substantially centrally of the formation and in easy reach of the compartments of each of the containers. The particular system to be followed in this distribution would be for the operator to open a corresponding compartment, No. 6 for instance, of a container carried in each rack and in distributing the wash of a particular customer, to put the whites in No. 6 of one rack, the lights in No. 6 of the adjacent rack, and the darks in No. 6 of the third rack, thus segregating the various classes of goods in each wash, whereupon the three said compartments would be closed. The compartment No. 5's of the same three racks would next be opened and the further operation of distribution similarly repeated. This method is carried out in the filling of the twenty-four compartments of each rack. After the clothes have been washed and the racks again returned and positioned, as shown in Fig. 12, the same order would be followed in the assembling of the several portions of the respective washes of the different customers, that is the corresponding compartments of the several similarly positioned receptacles would be opened simultaneously to collect the whites from one, the lights from another and the darks from the third, and then the three kinds of clothes put together to complete all the articles belonging to a single customer. When this method is followed all of the compartments of any one rack contain the same class of goods, as white, lights or darks, and the compartments of the several racks are treated for laundering separately and simultaneously in separate units when three units are used, or successively when one unit is used. Thus the washings of the several classes are kept separate, while such a relationship between the goods of the several washes is maintained that correct reassembly of all the goods of each wash is made easy.

45 I claim:

1. In combination a wash wheel having a frame defining an annular series of sector shaped pockets open at their ends, means for supporting said frame for rotation about the axis of said annular series of pockets, a reservoir in which said frame is positioned and having alined openings in its ends directly over the axis of rotation of said frame and opposite to which said open pocket ends may be successively presented, doors with downwardly converging side edges normally closing said openings, and clothes compartments insertable and removable through said openings into and out of said pockets.
- 30 2. The combination with a reservoir of a washing machine and a frame having an annular series of open ended pockets in said reservoir, a shaft for rotatably supporting said frame about the axis of said series, and extending beyond the end of said reservoir, said reservoir having an opening with which an end of each pocket may selectively be brought into registry by rotation of said frame, of a rack having a shaft which may be brought into axial alinement with said washing machine shaft, means for clutching said shafts together, a frame fixed to said rack shaft and having an annular series of open ended pockets similar to the pockets of said washing frame, and laundry receiving receptacles slidably fitting in said pockets and transferable by movement lengthwise of said shafts from one to the other of said frames through said opening when said shafts are in coupled relation.
- 35 3. The combination with a washing machine having a reservoir and a frame rotatable in said reservoir and having an annular series of open ended pockets, said reservoir having oppositely disposed end openings with which said pockets may be brought successively into registry, of a pair of racks each having a rotatable frame having an annular series of open ended pockets similar to the pockets of said machine frame, said racks being movable from and to positions with their respective pockets in axial alinement with the pockets of said machine frame, laundry receiving receptacles slidably fitting in said pockets whereby a receptacle in any of the pockets of said machine frame may be pushed out of said machine frame through one of said openings into a pocket of one of said racks by engagement therewith of a similar receptacle being pushed into the machine pocket through the opposite opening from the alined pocket of said other rack, and means for coupling the frames of said racks with said machine frame for simultaneous rotation.
- 40 4. A wash wheel comprising a central shaft, a frame carried by said shaft defining an annular series of pockets, removable clothes receptacles for said pockets, and means movable axially of said shaft for simultaneously clamping or unclamping said receptacles in said pockets.
- 45 5. A wash wheel comprising a central hollow shaft, a frame carried by said shaft defining an annular series of pockets extending along said shaft, a removable clothes receptacle for each of said pockets, a member movable axially through said hollow shaft, and means engageable with said receptacles and forcing them outwardly into clamping engagement with said frame when said member is moved in one direction and movable inwardly to release said receptacles on movement of said member in the opposite direction.
- 50 6. A washing machine comprising a reservoir, a rotary shaft extending axially of said reservoir, a frame fixed to said shaft and defining an annular series of pockets, the ends of said reservoir having sector shaped openings directly over said shaft for successive

registry with said pockets as said shaft is rotated, doors with downwardly converging side edges for normally closing said openings, and clothes receptacles insertable through one of said openings into the pockets presented successively in registry therewith, said receptacles being removable from said pockets through the other of said openings.

5 In testimony whereof I have affixed my
10 signature.
